Primary Examiner — Khawaja Anwar*Assistant Examiner* — Megan Tiana Rakos(74) *Attorney, Agent, or Firm* — Wolf, Greenfield & Sacks, P.C.(57) **CLAIM**

The ornamental design for a videotelephony apparatus, as shown and described.

DESCRIPTION

FIG. 1 is a bottom view of a videotelephony apparatus;

FIG. 2 is a front view thereof;

FIG. 3 is a front right perspective thereof;

FIG. 4 is a right side view thereof;

FIG. 5 is a rear view thereof;

FIG. 6 is a left side view thereof; and,

FIG. 7 is a top view thereof.

The broken lines in the figures show portions of the videotelephony apparatus that form no part of the claimed design.
